[57] CLAIM

The ornamental design for a curling iron, substantially as shown and described.

DESCRIPTION

FIG. 1 is a front elevational view of a curling iron embodying my new design and depicted in a closed position, the rear elevation view being the mirror image thereof;

FIG. 2 is a top plan view thereof;

FIG. 3 is a bottom plan view thereof;

FIG. 4 is a left side elevational view thereof;

FIG. 5 is a right side elevational view thereof; and
FIG. 6 is a perspective view of the design in an open position.

The broken line showing of a power cord is for illustrative purposes only and forms no part of the claimed design.
